CLAIM

The ornamental design for a smart shopping cart as shown and described.

DESCRIPTION

FIG. 1 is a top, front and right side perspective view of a smart shopping cart showing our new design;

FIG. 2 is a bottom, rear and left side perspective view thereof;

FIG. 3 is a front elevational view thereof;

FIG. 4 is a rear elevational view thereof;

FIG. 5 is a right side view thereof;

FIG. 6 is a left side view thereof;

FIG. 7 is a top plan view thereof;

FIG. 8 is a bottom plan view thereof;

FIG. 9 is an enlarged view of portion 9 in FIG. 1; and,

FIG. 10 is an enlarged view of portion 10 in FIG. 1.

The broken lines in the drawings illustrate portions of the smart shopping cart which form no part of the claimed design. The dash-dot-dash lines in FIGS. 1, 9 and 10 are demarcating the enlarged views shown in FIGS. 9 and 10.
